UNITED STATES PATENT OFFICE.

LEWIS WILKINSON, OF CHICAGO, ILLINOIS; FREDERICK M. STEELE, ADMINISTRATOR OF SAID LEWIS WILKINSON, DECEASED.

TURN-BUCKLE.

SPECIFICATION forming part of Letters Patent No. 328,443, dated October 13, 1885.

Application filed October 25, 1884. Serial No. 146,505. (No model.)

To all whom it may concern:

Be it known that I, LEWIS WILKINSON, a citizen of the United States, residing at Chicago, in the county of Cook and State of Illinois, have invented certain new and useful improvements in Turn-Buckles, of which the following is a specification, to wit:

This invention relates to turn-buckles; and it consists in certain peculiarities of the construction of the same, substantially as will be hereinafter more fully set forth and claimed.

In order to enable others skilled in the art to which my invention appertains to make and use the same, I will now proceed to describe its construction and operation, referring to the accompanying drawings, in which—

Figure 1 is a side elevation, and Fig. 2 a central vertical section of my invention.

A represents the heads or ends of my turn-buckle, into which are screwed the rods *a a*, which are to be tightened by either a right or left hand screw-thread, as required, and B B are the bars forming the sides of the buckle and connecting the heads together. These bars B have commonly been welded to the heads or end bars, and as this welding is often imperfect, and the imperfection not detected till the device is put in use, breakage often

occurs when a strain is put upon them, and there is no way of ascertaining the strength till an actual test is made. To obviate this, I provide the bars B with right and left screw-threads *b*, which enter similarly-threaded holes *b'* in the heads, and form a firm connection, the strength of which can always be calculated without difficulty before the article is taken from the shop.

While I design to make these turn-buckles of any size required they are especially valuable for large and heavy work where the most annoyance has been felt at the large number of breakages in using the welded ones.

Having thus fully described my invention, what I claim as new, and desire to secure by Letters Patent, is—

A turn-buckle having its side bars secured in the ends or heads by right and left screw-threads, substantially as and for the purpose set forth.

In testimony whereof I affix my signature in presence of two witnesses.

LEWIS WILKINSON.
